Filed Apr. 28, 1975, Ser. No. 572,501

Term of patent 14 years

Int. Cl. D6—99

U.S. Cl. D6—5

FIG. 1 is a perspective view of a closable dressing table for an infant embodying the features of the present invention and illustrating the dressing table in its open configuration;

FIG. 2 is a perspective view similar to FIG. 1 but on a slightly reduced scale and showing the dressing table in its closed configuration and as mounted on a vertical supporting wall;

FIG. 3 is a perspective view of the rear side of the dressing table in its closed configuration, the rear side normally facing the vertical supporting wall, and further showing the lower hinged side edge; and

FIG. 4 is a perspective view of the dressing table in its open position.

The dotted lines shown in FIG. 4 are for illustrative purposes only.

We claim:
The ornamental design for a closable dressing table for an infant, substantially as shown and described.
